UNITED STATES PATENT OFFICE.

HARRY F. PORTER, OF TRENTON, NEW JERSEY, ASSIGNOR OF ONE-HALF TO
CORNELIUS D. EHRET, OF PHILADELPHIA, PENNSYLVANIA.

CURRENT-RECTIFYING SYSTEM.

Application filed February 16, 1925. Serial No. 9,446.

My invention relates to a method of and apparatus for converting, as by rectification, alternating or fluctuating current into direct current for general purposes, and more particularly for supplying current to vacuum tubes, and particularly those of the type utilized in radio systems and kindred relations.

My present invention is of the general character disclosed in my prior application Serial No. 756,376, filed December 17, 1924.

In accordance with my invention, there may be utilized a lesser number of series of thermo-couples than in the Wheatstone bridge arrangement of the aforesaid prior application, by passing the fluctuating or alternating current through two series of thermo-couples in parallel, with the two series of thermo-couples connected cumulatively with respect to the direct current circuit to be supplied thereby, and effecting a balance as regards fluctuating or alternating electro-motive-forces at the extreme direct current terminals of the two series, whereby there is no fluctuating or alternating electro-motive-force impressed upon the direct current circuit, with the result that there is no hum or similar disturbing effect in the direct current circuit.

In one of its aspects, my invention comprises a Wheatstone bridge arrangement of the general character of the aforesaid prior application, with the substitution for two of the thermo-couple series in two arms of the bridge of condensers, at least one of them preferably accompanied by a balancing resistance; and more particularly, the inclusion in such arms of the bridge of transformer secondaries, preferably in the form of bifilarly wound secondary coils, with which is associated a primary winding traversed by the fluctuating or alternating current, with the result, in effect, that there are introduced into two arms of the bridge two sources delivering fluctuating or alternating currents in phase with each other, and preferably of substantially equal amplitudes.

Further in accordance with my invention, several of the above described circuit arrangements are utilized for procuring direct currents of different voltages suited to different uses, particularly in radio apparatus involving a plurality of vacuum tubes.

My invention resides in the method and apparatus of the character hereinafter described and claimed.

For an understanding of my method, and for an illustration of various features of my invention, reference is to be had to the accompanying drawings, in which:

Fig. 1 is a diagrammatic view of a circuit arrangement embodying my invention.

Fig. 2 is a diagrammatic view of a modified circuit arrangement.

Fig. 3 is a diagrammatic view of a radio system embodying the arrangement of Fig. 2.

Fig. 4 is a diagrammatic view of radio apparatus comprising a plurality of vacuum tubes with a plurality of arrangements of the character of Fig. 2 for supplying direct currents of different voltages.

Referring to Fig. 1, T and T¹ are two series of thermo-couples whose alternate junctions are hot and cold and whose hot junctions are preferably locally of restricted cross section and/or higher resistance, whereby the alternating or fluctuating current passed therethrough raises them to suitably high temperature above that of the cold junctions to develop suitably high thermo-electro-motive-force. The two series T and T¹ are in series with each other between the points 1 and 2, so that the thermo-electro-motive-forces of all thermo-couples of both series are added or cumulative between the points 1 and 2, which are in effect the terminals of the direct current source T, T¹ for supplying smooth direct current to any suitable consumption circuit, such, for example, as the anode circuit of an audion or vacuum tube V having the anode a, filament or cathode f and the usual grid g. The thermo-couple series T and T¹ may be considered as arms of a Wheatstone bridge, in whose other arms are disposed the condensers K and K¹. To the points 3 and 4 is connected the source of fluctuating or alternating current, generically indicated at S, and which may be, for example, a source of alternating current which may be connected to the points 3 and 4 through an ordinary lamp socket. The source S is therefore in effect in a conjugate conductor of the Wheatstone bridge, while the consumption device V is in the other conjugate conductor traversed only by direct current. To ensure that between the points 1

100 105 110

and 2 there is never a difference of fluctuating or alternating potential, there may be utilized in addition to the condensers nicely to balance the bridge an adjustable resistance or rheostat R. The condensers K are of suitably large capacity to pass to the thermo-couple series T and T¹ current of the desired magnitude, at the potential available from the source S. These condensers serve additionally to prevent any short circuit of the direct current between the points 1 and 2 or to the fluctuating or alternating current circuit.

In Fig. 2 the arrangement is generally similar to that of Fig. 1, except that there are included in the arms with the condensers K and K¹ the windings s and s¹, constituting secondaries of a transformer whose primary p is brought into circuit with the source of alternating or fluctuating current S. The windings s, s¹ have a common terminal at 4, and their remote ends rise and fall in potential in phase with each other, with the result that between the conjugate points 1 and 2 of the bridge there never exists a difference of fluctuating or alternating potential, with the result, as in Fig. 1, that in the anode circuit of the tube V there will be no component of fluctuating or alternating current due to the source S, and there will therefore exist no hum- or noise-producing current, particularly when the current delivered by the source S is of audio frequency, as, for example, 60 cycles per second, commonly employed on commercial lighting and power circuits.

In Fig. 3 there is shown generically a radio system, such, for example, as a radio receiving system involving a vacuum tube V, whose cathode or filament is heated by any suitable source of current, as b. In Fig. 3 V represents generically either a radio frequency amplifier, a detector, or an audio frequency amplifier, it being understood that the source of direct current available in accordance with my invention may be applied to a vacuum tube of any type used for any purpose. In the example illustrated, the input or grid circuit of the tube V is inductively coupled to an antenna or other absorption structure A through the transformer t, whose secondary circuit is tuned by the variable condenser C. In the anode circuit is the winding W, which, when the tube V is a radio frequency amplifier, may be the primary of a radio frequency transformer whose secondary is connected in the grid circuit of the succeeding tube. Or when the tube V is utilized as a detector, the winding W may be an audio frequency winding, such as the winding of a telephone receiver, or the primary of an audio frequency transformer whose secondary is in the grid circuit of a succeeding audio frequency amplifying tube; or if the tube V is an audio frequency amplifier, the winding W may be a telephone winding or the primary of an

audio frequency transformer whose secondary connects with the grid circuit of a succeeding audio frequency amplifier.

The source of anode circuit current is of the general character indicated in Fig. 1, and more specifically of the character indicated in Fig. 2. The primary p is in circuit with the source of alternating or fluctuating current S, and associated with the same core e of the transformer are the secondary windings s and s¹. As indicated, the windings s and s¹ are wound bifilarly, which is an advantage in that all portions of each of the windings s and s¹ are subjected to exactly similar conditions, whereby all differences of fundamental and harmonic frequencies are balanced, and there is afforded substantially absolute similarity of phase of the two windings s and s¹, so overcoming or balancing out effects which might otherwise be caused by magnetic leakage or difference in magnetic leakage as between the two coils s, s¹ and the primary p. Furthermore, the conductors of the windings s, s¹ are preferably of similar material, cross section and length, whereby their increases in resistance due to heating will be equal, further contributing to effecting a complete balance of the circuit. As before, if any unbalance remains, the circuit may be re-balanced by the resistance R.

In Fig. 4 there is shown a radio receiving system comprising, as well understood in the art, a radio frequency amplifier tube V¹, a detector tube V², and an audio frequency amplifier V³, in whose plate circuit is the telephone or loud speaker M. The direct current for the anode circuit of the detector tube V² is derived from the two thermo-couple series T, T¹ in an arrangement of the character of Fig. 2 involving the transformer secondaries s and s¹, coupled to the primary p, in turn connected with the source S. The positive terminal of the two series T, T¹ is connected by conductor 5 to the anode of the tube V², and the negative terminal is connected by conductor 6 with the filament or cathode f. The conductor 6 connects also with the cathodes f of the radio and audio frequency amplifier tubes V¹ and V³, respectively, on whose anode circuits is utilized higher voltage than supplied by the thermo-couple series T, T¹. For this purpose there is provided a second series T², T³, cumulative with each other and with the series T, T¹, to effect between the conductor 6 and the conductor 7 a suitably high electro-motive-force, the conductor 7 communicating with the anodes a of the tubes V¹ and V³. Associated with the thermo-couple series T² and T³ in the same general arrangement are the transformer secondaries s² and s³, the condenser K serving for both groups T, T¹ and T², T³, and the condenser K² and resistance R¹ serving for the branch or arrangement involving the series T² and T³ only.

Similarly, where it is desirable to impress a suitable negative potential upon the grid of a tube, as, for example, upon the grid g of the audio frequency amplifier V^3 , there is supplied a further smaller series of thermo-couples T^4 , T^5 associated with the transformer secondaries s^4 , s^5 , the condenser K^1 serving also for this branch or system and the additional condenser K^3 serving for the series T^4 , T^5 only. The negative terminal of the series T^4 , T^5 connects by conductor 8 with the grid of the tube V^3 , while the positive terminal of the series T^4 , T^5 connects with the conductor 6 communicating with the cathode f of the tube V^3 .

In the arrangements of both Figs. 1 and 2, the thermo-couple series T and T^1 are traversed in parallel by the fluctuating or alternating current, and a balance between the remote terminals 1 and 2 of the two series is effected by simpler and cheaper means than by further series of thermo-couples, as by the condensers K , K^1 , supplemented when necessary by the resistance R . The condensers K , K^1 comprise means for balancing between the remote terminals 1 and 2 of the thermo-couple series and serve also as means for preventing short circuit of direct current through the alternating or fluctuating current source or, in general, between the terminals 1 and 2.

While I have hereinbefore described the application of direct thermo-electric current to the anode and grid circuits of audions or vacuum tubes, it will be understood that a generally similar arrangement may be utilized for supplying direct current to the filament or cathode f , in which case the terminals of the filament will be connected to the terminals 1 and 2, preferably without an intervening rheostat, though such may be employed if desirable. In this case, however, inasmuch as the filament current is great as compared to the anode circuit current, the condensers K and K^1 must have far greater capacities than in the arrangement of Figs. 1 and 2 for supplying anode circuit current. In some instances, the capacities for filament excitation would be exceedingly large, and in general, therefore, my arrangement is more generally suitable for anode circuit excitation; and accordingly, in Figs. 3 and 4 filament-exciting batteries b are utilized.

The hot junctions of the thermo-couples herein referred to are preferably out of direct heat-transfer relation with the atmosphere, and are preferably embedded in material of low heat conductivity and of electrical insulating character, such, for example, as refractory electrically non-conducting mineral matter, whereby the temperatures of the hot junctions are maintained high. Cold junctions may be in contact with the atmosphere, or may be maintained by

artificial means at sub-atmospheric temperature. 65

While I have herein indicated resistances, as R and R^1 , to effect nicety of balance, it will be understood that any equivalent means may be used. For example, in shunt to one or the other of the condensers K , K^1 may be used a smoothly variable condenser. Further, it will be understood that the extreme terminals of the resistance R may be in the adjacent bridge arms, and that at 4 there may be used a contact slideable along the slide wire resistance to effect balance. 70 75

To use the condensers K , K^1 and the like at maximum voltage to which they may be suited, or to utilize condensers K , K^1 or the like of smaller capacity, the circuit of the source containing the condensers may be rendered resonant, as, for example, by utilizing the adjustable inductance L , as indicated in Figs. 1 and 2. In case, however, the inductances of the windings s , s^1 , Fig. 2, are greater than necessary for resonance, then in lieu of the inductance L of Fig. 2 there may be utilized a variable condenser. And if the inductance predominates in the arrangement 90 of Fig. 1, there may be used in lieu of the adjustable inductance L a variable condenser. 95

By adjusting the circuits to resonance as described, the capacities, such as K and K^1 , may be smaller than in the case the circuit is non-resonant; and accordingly, by the utilization of resonance, the arrangement of both Figs. 1 and 2 may as well be utilized for supplying current to the filaments or cathodes of vacuum tubes, for notwithstanding the greater current required and ordinarily greater capacities for the condensers K , K^1 , resonance makes it possible to procure these large filament-exciting currents with reasonable magnitudes of capacities of the condensers K and K^1 . 100 105

What I claim is:

1. In a system for deriving direct from fluctuating or alternating current comprising capacities and thermo-couples, the method which comprises passing fluctuating or alternating current through said capacities and thermo-couples while disposed in parallel paths with respect to the fluctuating or alternating current, effecting by said capacities zero fluctuating or alternating potential differences between the remote terminals of the thermo-couple paths, and taking off direct current through said remote terminals. 110 115

2. A system for deriving direct from alternating or fluctuating current, comprising a source of fluctuating or alternating current, paths traversed in parallel by current from said source and containing thermo-couples, the thermo-couples in said paths being disposed cumulatively in series with each other between terminals of a direct current circuit, 125 120

and capacitative means for effecting substantially zero difference of fluctuating or alternating potential between said terminals.

3. A system for deriving direct from alternating or fluctuating current, comprising a source of fluctuating or alternating current, paths traversed in parallel by current from said source and containing thermo-couples, the thermo-couples in said paths being disposed cumulatively in series with each other between terminals of a direct current circuit, and capacitative means and a resistance for effecting substantially zero difference of fluctuating or alternating potential between said terminals.

4. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, and means for passing alternating or fluctuating current through the other conjugate terminals of the bridge.

5. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, means for passing alternating or fluctuating current through the other conjugate terminals of the bridge, and a balancing resistance in one of said bridge arms.

6. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, and sources of fluctuating or alternating current in the bridge arms including said capacities.

7. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, and a balancing resistance in one of said bridge arms.

8. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, and transformer secondaries in said bridge arms with said capacities.

9. A system for deriving direct from alternating current comprising a Wheatstone

bridge, thermo-couples in adjacent arms of said bridge, capacities in the other arms of said bridge, said thermo-couples disposed cumulatively in series between conjugate terminals of said bridge, a transformer, a source of fluctuating or alternating current in circuit with the primary of said transformer, and bifilarly wound secondaries of said transformer disposed in said bridge arms with said capacities.

10. A system for supplying to an electrode circuit of a vacuum tube direct current derived from alternating or fluctuating current, comprising a source of fluctuating or alternating current, paths traversed in parallel by current from said source and containing thermo-couples, the thermo-couples in said paths being disposed cumulatively in series with each other between terminals of a direct current circuit, and capacitative means for effecting substantially zero difference of fluctuating or alternating potential between said terminals.

11. A system for supplying to an electrode circuit of a vacuum tube direct current derived from alternating current comprising a Wheatstone bridge, thermo-couples in adjacent arms of said bridge, capacities in the other arms of said bridge, said thermo-couples disposed cumulatively in series between conjugate terminals of said bridge, and a source of fluctuating or alternating current connected to the bridge arms including said capacities.

12. A system for deriving direct from alternating current comprising a Wheatstone bridge, thermo-couples in adjacent arms of said bridge, capacities in the other arms of said bridge, said thermo-couples disposed cumulatively in series between conjugate terminals of said bridge, means for passing alternating or fluctuating current through the other conjugate terminals of the bridge, a second similar bridge having a capacity-containing arm in common with the capacity-containing arm of said first named bridge, and the thermo-couples of both bridges connected cumulatively in series with each other.

13. A system for deriving direct from alternating current for supplying radio receiving apparatus having a plurality of thermionic vacuum tubes, comprising a Wheatstone bridge, thermo-couples in adjacent arms of said bridge, capacities in the other arms of said bridge, said thermo-couples disposed cumulatively in series between conjugate terminals of said bridge, means for passing alternating or fluctuating current through the other conjugate terminals of the bridge, and a second similar bridge having a capacity-containing arm in common with the capacity-containing arm of said first named bridge, the thermo-couples of both bridges connected cumulatively in series with each

other, the anode circuits of said vacuum tubes being supplied respectively by the thermo-couples of the different bridges.

14. A system for deriving direct from alternating current for supplying radio receiving apparatus having a plurality of thermionic vacuum tubes, comprising a Wheatstone bridge, thermo-couples in adjacent arms of said bridge, capacities in the other arms of said bridge, said thermo-couples disposed cumulatively in series between conjugate terminals of said bridge, means for passing alternating or fluctuating current through the other conjugate terminals of the bridge, and a second similar bridge having a capacity-containing arm in common with the capacity-containing arm of said first named bridge, the thermo-couples of both bridges connected cumulatively in series with each other, and the

thermo-couples of one of said bridges supply- 20
ing current to the anode circuit of said tube, and the thermo-couples of another of said bridges impressing a biasing voltage upon the grid of said tube.

15. A system for deriving direct from 25
alternating or fluctuating current, comprising a source of fluctuating or alternating current, paths traversed in parallel by current from said source and containing thermo-couples, the thermo-couples in said paths 30
being disposed cumulatively in series with each other between terminals of a direct current circuit, capacitative means for effecting substantially zero difference of fluctuating or 35
alternating potential between said terminals, and means for rendering resonant the circuit of said capacitative means.

HARRY F. PORTER.

CERTIFICATE OF CORRECTION.

Patent No. 1,696,210.

Granted December 25, 1928, to

HARRY F. PORTER.

It is hereby certified that error appears in the printed specification of the above numbered patent requiring correction as follows: Page 1, line 77, for the word "of" read or; page 5, line 6, claim 14, strike out the words "plurality of", and line 7, for "tubes" read tube; and that the said Letters Patent should be read with these corrections therein that the same may conform to the record of the case in the Patent Office.

Signed and sealed this 5th day of August, A. D. 1930.
